UNITED STATES PATENT OFFICE

1,995,210

PAPER BOTTLE

Reinhold Leibfarth, Metzingen-Wurtemberg,
GermanyApplication October 2, 1930, Serial No. 485,887
In Germany February 28, 1930

3 Claims. (Cl. 229—5.6)

This invention relates to paper bottles and more especially to a novel closure for paper bottles, as well as to a novel paste or glue to be used in connection with the several layers or parts of 5 paper or similar material of which the paper bottle is composed. My present invention comprises further improvements of the bottle or container described in my co-pending application for U. S. Patent Serial No. 442,384, filed April 7, 1930.

10 According to my present invention I provide a special closure for paper bottles, especially for the purpose of being suitable for use as a receptacle for nutriments and the like. More particularly, the closure forming part of my present invention is especially designed to be used in connection with paper bottles of flat conical conformation.

15 In addition to the novel closure I provide a novel glue or paste adapted to serve as a binding or re-inforcing substance for properly uniting the several layers of which the wall of the bottle is composed as well as for fastening the bottom to the walls of a paper bottle.

20 The closure is so constructed according to my invention that it will provide the greatest degree of safety against accidental or malicious opening of the bottle. In addition to this, my novel closure is particularly designed for the purpose of preventing withdrawal of the contents of the bottle 25 in that the closure, after being once opened, cannot be again closed without indicating the fact of previous opening.

25 An essential feature of my novel closure consists in that it is made in the form of a seal of sheet metal applied to the rim of the mouth of the bottle, after having said rim pressed flat, said seal after being applied to said rim presenting an essentially U-shaped cross-section. After being applied in this manner to the rim of the bottle this 30 seal is preferably provided with depressions which penetrate into the compressed rim of the bottle. Preferably, in the present case said depressions are of a conformation to prevent lateral displacement of the seal or closure with respect to the 35 compressed rim of the bottle, a wave shaped or curved conformation being preferably given for this purpose to said depressions. In addition to this the depressions on the seal or closure may include for instance a depressed inscription such as the week day or day of a month on which the closure had been applied to the bottle.

40 In the accompanying drawing Fig. 1 is an elevation of my new paper bottle showing in particular the novel closure provided at the compressed mouth of the bottle, and Fig. 2 a partial lateral

view of the upper part of the bottle and closure shown in Fig. 1.

45 In the drawing *a* designates the paper wall of the bottle in condition of being closed by pressing the rim of the mouth of the bottle together so as to give a flat conical conformation to the entire wall of the bottle. The wall *a* of the bottle is composed of several layers of water-proof paper, said layers having been united with each other by means of a paste or glue in the form of the aforementioned novel binding and re-inforcing substance. The bottom *b* of the bottle is preferably inwardly arched and fastened to the under rim of the wall of the bottle likewise by the aid of said paste or glue. The inwardly arched form of the 50 bottom *b*, as indicated at *d*, will have the effect that the weight of the liquid contained in the bottle will exert a proper pressure upon said bottom so that the latter with its downwardly bent rim will be firmly pressed against the interior 55 periphery of the under portion of the wall of the bottle. At the upper end, that is to say, at the mouth of the bottle the rim of the wall is pressed together after the contents have been filled-in, so that the two parts of said rim *e* and *f* will be 60 positioned flat one upon the other. The so compressed flat upper or mouth portion of the bottle may now be folded together and the aforementioned seal or closure proper placed upon the folded portion and the seal or closure may now be applied so as to grip in the form of a U around both 65 outer surfaces of the mouth portion in flat compressed condition. The depression *h* which serves for fastening the seal or closure *g* to the closed mouth of the bottle is of proper depth permitting 70 penetration of said depressions into the outer surfaces of the folded portions of the mouth of the bottle. The depressions or impressions *h*, for instance, may be made in the form of a wave 75 (curve) which runs in longitudinal direction along the seal or closure *g*, as indicated in Fig. 1 and an abbreviated designation "Mo"—which means Monday—may likewise be impressed into said seal or closure. Evidently, the wave-shaped conformation of the depression will essentially serve to 80 prevent any lateral displacement of the seal or closure *g* upon the compressed rim of the mouth of the bottle.

85 My novel closure may be very conveniently and easily applied to the paper bottle after having introduced the contents and will most successfully meet all requirements of a practical closure for paper bottles of the present kind. A paper bottle provided with the novel closure according to my present invention has the further advantage that 90

the bottles may be most conveniently packed in pairs by placing one bottle in opposite direction to another which is of especial importance with respect to utilizing a given space of a box.

5 A further novel feature of my present invention, as above mentioned, consists in providing an efficient binding and re-inforcing glue or paste for suitably uniting with each other the several layers of which the wall of the bottle is composed 10 as well as for fastening the bottom to the under edge of the wall of the bottle.

15 The novel glue or paste which I use according to my present invention for uniting with each other the several layers of which the wall of the bottle is composed as well as for fastening the bottom to the under edge of the wall of the bottle is composed essentially of acid-free casein, albumen and sugar. The constituents may for instance be mixed in the following proportions:

20 1 kg. of casein,
30 g. of crystalline borax (borate of soda),
55 ccm. of ammonium chloride,
135 g. of pulverized white sugar, and water.

25 The process of making my new glue or paste is carried out as follows:

30 1 kg. acid-free neutral casein is mixed with 30 g. of crystalline borax and placed into a container of aluminum. Cold water is now added to the mixture and at the same time the latter is continuously kneaded. Thereupon 4 l. of cold water is added and subsequently 4 l. of warm water having a temperature of about 70° C. and 55 ccm. of ammonium chloride are added under constant 35 stirring of the mixture. Finally the white of an egg and thereupon 135 g. of pulverized sugar are added and the mass well stirred.

40 In this manner a permanent and durable glue or paste will be obtained which is most suitable for the present purpose and does not produce any bubbles or foam during working of the mass by machine means, said glue or paste having the further valuable property of not exerting any injurious effect upon the contents in the bottle. Furthermore, the glue or paste so obtained is insoluble 45 in water and absolutely free from odor. As regards the special mode of applying my new glue or paste to the paper wall of the bottle it may be remarked that it may be applied either manually, 50 for instance by means of a brush, or also by machine means.

If after some longer time of standing the glue or paste should become viscous, it may be diluted

with luke-warm water to diminish the viscosity. The glue or paste moreover, will become effective with respect to its binding property upon the several layers of paper to be re-inforced and united with each other after properly heating the same.

5 The tools or implements, such as mandrels, sleeves, stamps or the like, which are used for making the paper bottle, are properly heated for the purpose of rendering the glue or paste effective.

10 While I have herein described a preferred form which my invention may take, it should be understood that it is not necessary that the depression formed in the seal be in the shape of a smooth curve or wave, because obviously certain of the advantages of the invention may also be secured with any other non-straight form of depression, the expression "crooked" being employed in the 15 claims as a generic term designating such non-straight shape and being broad enough to cover 20 smooth curves or waves, as well as other forms of depressions.

I claim:

1. A closure for paper bottles adapted to hold 25 liquids, said closure comprising the collapsed rim portion of the bottle neck and a U-shaped metallic clip having at least one end open, and having therein a longitudinal bead-like impression terminating at the open end and impressed within the material of the paper, for securing it thereover in non-slidable interlocking relation, said bead being longitudinally crooked.

2. A closure for paper bottles adapted to hold 30 liquids, said closure comprising the collapsed and folded-over rim portion of the bottle neck and a 35 U-shaped metallic clip having at least one end open, and having therein a longitudinal bead-like impression terminating at the open end and impressed within the material of the paper, for securing it thereover in non-slidable interlocking 40 relation, said bead being longitudinally crooked.

3. A closure for paper bottles adapted to hold 45 liquids, said closure comprising the collapsed and folded-over rim portion of the bottle neck and a U-shaped metallic clip having at least one end open, and having therein a longitudinal bead-like impression terminating at the open end and impressed within the material of the paper, for securing it thereover in non-slidable interlocking 50 relation, said bead being longitudinally undulating.

REINHOLD LEIBFARTH.
